UNITED STATES PATENT OFFICE.

JAMES C. STEELE, OF STATESVILLE, NORTH CAROLINA.

BRICK-TRUCK.

SPECIFICATION forming part of Letters Patent No. 398,985, dated March 5, 1889.

Application filed October 23, 1888. Serial No. 288,979. (No model.)

To all whom it may concern:

Be it known that I, JAMES C. STEELE, of Statesville, in the county of Iredell and State of North Carolina, have invented a new and 5 useful improvement in Brick-Trucks, of which the following is a specification.

My invention is in the nature of an improvement upon the brick-truck for which I received Letters Patent No. 380,603, dated April 10, 1888; and it consists in the peculiar construction and arrangement of the rests or supporting-arms for carrying the load and means for operating the same, and also in the arrangement of the axle-arms for the wheels, 15 whereby they are also made to act as braces for the frame-work.

Figure 1 is a perspective view of the truck about to be applied to a platform supporting a pile of bricks, and Fig. 2 is a longitudinal 20 vertical section of the truck.

In the drawings, A A represent the truck-wheels, which are about thirty inches in diameter, formed with sixteen metal-rod spokes arranged in the hub in zigzag fashion. The 25 spokes are screwed into the hub and have nuts screwed on the other end of the spokes on the inside of the tire or rim, with which to set and true the wheel, the spokes then being riveted through the tire.

30 B B C D E represent the wooden framework of the truck, of which B B are longitudinal side bars; C, a rear cross-bar forming a handle, and D E two parallel cross-bars near the middle of the frame.

35 F are the axle-arms, upon which the wheels turn. These arms are bent up and extend along the inside of the side bars for a short distance, and are bolted to the same at a, and then extending obliquely across the right 40 angle between the side bars and first cross-bar are bolted to the said cross-bar at b, thereby forming a brace for this joint of the frame-work, which greatly strengthens the same and at the same time forms a solid and 45 strong connection for the axle-arms.

G G are rests or supporting-arms which are bent into shape from a single piece of stout metal, which is made to assume a bail shape with the bend in the middle at the rear and 50 its two arms at the front. The front ends of these arms or rests are supported by link-bars

H, which at their upper ends are jointed to the middle of elbow-levers I. At their lower and rear ends these elbow-levers are fulcrumed to the frame-work near the wheel-hubs, while their upper ends are jointed to rods J, that extend back to and are jointed to a bail-shaped handle, K, fulcrumed to the side bars. By drawing this bail-handle to the rear the rests or supporting-arms G are raised, 60 while the reverse motion of the handle lowers them. To the middle of the bent rod which forms the rests or supporting-arms is attached a supporting-chain and a rod, L, having a hand-hold at its upper end. This rod passes 65 through a guide-loop, e, on the cross-bar E, and serves to steady the supporting-arms while being pushed under the pack of bricks or being pulled out from under the same.

The rests or supporting-arms G G occupy 70 a position a short distance above the ground, and are designed to be pushed under the raised and projecting ends of a platform, P, carrying a load of bricks. When the arms are thus pushed under the projecting ends of 75 the platform, the arms are at their lowest position, with the bail-shaped handle K lying over to the front close to the loop or handle of rod L. The bail-handle is now grasped and drawn upwardly and to the rear. This 80 action raises the rests or supporting-arms G G at their front points of support. The rear end is raised by raising the handle of the truck at the same time that the bail is drawn back, thus lifting the load of bricks in a perfectly level position by a simultaneous motion of the bail-shaped lever and the handle of the truck.

Having thus described my invention, what I claim as new is—

1. The combination, with a wheeled truck, of a pair of rests or lifting-arms, G G, arranged between the wheels and near the ground, and lifting mechanism for both the front and rear ends of said arms to raise and 95 lower the same in level position, as described.

2. The combination, with a wheeled truck, of a pair of rests or lifting-arms, G G, arranged between the wheels and near the ground, link-bars H, connecting with the front 100 ends of the arms, elbow-levers I, jointed to the links, rods J J, connected to the elbow-

levers, and bail-shaped handle K, connected to the rods J, substantially as and for the purpose described.

3. The combination, with the wheeled truck, 5 of the rests or arms G G, formed at the front end of a bent bar, lift-rod L, connected to the middle portion of the bent arms, and the links H, elbow-levers I, rods J, and bail K, connected to and operating the front ends of the 10 rests or arms, as described.

4. The combination, in a truck, with the longitudinal side bars and the cross-bar connecting the same, of the axle-arms extended inside the longitudinal bars and across the angle to the cross-bar to form a brace, as de- 15 scribed.

JAMES C. STEELE.
